UNITED STATES PATENT OFFICE.

WILLIAM FRANKLIN BOWEN, OF CHICAGO, ILLINOIS.

DESIGN FOR A BADGE.

SPECIFICATION forming part of Design No. 21,443, dated April 5, 1892.

Application filed February 23, 1892. Serial No. 422,590. Term of patent 3½ years.

To all whom it may concern:

Be it known that I, WILLIAM FRANKLIN BOWEN, residing at Chicago, in the county of Cook and State of Illinois, have invented and produced a new and original Design for a World's Fair Badge, of which the following is a specification, reference being had to the accompanying drawing, forming part thereof.

The drawing shows a front view of my newly-designed badge.

The leading feature of my design consists of a spherical map of the world or globe suspended within an encircling ring from a medal.

In the drawing, A is the medal, which in the instance illustrated consists of a disk, which bears imprinted upon it a bust of Columbus in the central portion and around the margin the words "World's Columbian Exposition."

B is the globe or spherical map of the world, which is mounted upon its polar axis in the ring C, the latter being suspended by a link

from the lower edge of the medal. I sometimes print upon the globe the words "World's Fair," and these words are shown in the drawing placed equatorially on the map.

25

D in the drawing indicates a ribbon, by means of which the badge can be attached to the buttonhole of a wearer, if desired; but I make no claim to the words "World's Fair" nor to the words "World's Columbian Exposition," and these words may be omitted or replaced by others.

I claim—

The design for the World's Fair badge, herein shown and described, the same consisting of the medal, the ring suspended therefrom, and the globe within said ring.

35 WILLIAM FRANKLIN BOWEN.
